FIG 4

FIG 5

FIG 6

FIG 7

FIG 8

FIG 9

FIG 10

FIG 11

FIG 12

FIG 13

FIG 14

FIG. 1 is a front elevational view of a hair curler showing my new design;

FIG. 2 is a right side elevational view;

FIG. 3 is a top plan view;

FIG. 4 is a bottom plan view;

FIG. 5 is an enlarged sectioned view taken along line 5-5 in FIG. 1;

FIG. 6 is an enlarged sectioned view taken along line 6-6 in FIG. 1;

FIG. 7 is an enlarged sectioned view taken along line 7-7 in FIG. 1;

FIG. 8 is a front elevational view of a hair curler showing a modified form of my new design;

FIG. 9 is a right side elevational view thereof;

FIG. 10 is a top plan view;

FIG. 11 is a bottom plan view;

FIG. 12 is an enlarged sectional view taken along line 12-12 in FIG. 8;

FIG. 13 is an enlarged sectional view taken along line 13-13 in FIG. 8; and

FIG. 14 is an enlarged sectional view taken along line 14-14 in FIG. 8.

I claim:

The ornamental design for a hair curler, as shown and described.
